FEED MECHANISM FOR LATHES

Richard K. Le Blond and Harry C. Kemper, Cincinnati, Ohio, assignors to The R. K. Le Blond Machine Tool Company, Cincinnati, Ohio, a corporation of Delaware

Application July 16, 1936, Serial No. 90,940

15 Claims. (Cl. 82—21)

This invention pertains to tool feeding mechanism for lathes, and in particular to mechanism for actuating the carriage and cross slide of engine lathes.

5 One object of our invention is to provide in a lathe apron, a mechanism for obtaining the necessarily complete range of threads and feeds for the tool carriage. Another is to provide control means conveniently located on the apron for 10 selecting the various threads and feeds desired.

Still another object is to provide means in connection with the thread and feed change mechanism so that selection of various threads and feeds may be accomplished while the lathe tool is 15 in cutting operation.

An object is also to provide a simplified and easily operated control lever for alternately selecting the cross or longitudinal feeding motions for the carriage.

20 Again, an object is to provide a simplified interlocking mechanism to prevent simultaneous engagement of the half-nuts on the lead screw and the feeding motion to the carriage or cross slide.

25 A further object of our invention is to provide a novel rapid traverse mechanism for longitudinally moving the tool carriage in either direction on the lathe bed.

The rapid traverse mechanism is unique in that 30 it may be rendered operative to traverse the carriage in either direction irrespective of whether the feed mechanism is engaged or disengaged.

The rapid traverse mechanism is also arranged so that damage is prevented when the carriage is 35 traversed into obstructions such as the headstock or tailstock of the lathe, or when the latter is operated with the half-nuts in engagement with the lead screw.

40 It is also our object to provide means in connection with the traverse mechanism to prevent a rapid rotation of the hand wheel for longitudinal movement of the carriage when the carriage is being normally actuated in rapid traverse.

45 These and other objects of our invention which will be set forth hereinafter or will be apparent to one skilled in the art, we accomplish by that certain construction and arrangement of parts of which we now describe an exemplary embodiment.

50 Reference is made to the drawings, wherein Fig. 1 is front elevation in perspective of a typical application of our invention to an engine lathe.

55 Fig. 2 is an enlarged front elevation in perspective of the lathe apron.

Fig. 3 is a left hand end elevation of the rapid traverse control box mounted on the front of the lathe bed.

Fig. 4 is a front elevation of the rapid traverse control box showing, in addition, a portion of the 5 left hand end of the lathe apron.

30

Fig. 14 is an end elevation partly in section on the line XIV—XIV of Fig. 4.

Fig. 15 is an end elevation partly in section on the line XV—XV of Fig. 8.

35

The invention is shown in the exemplary embodiment as applied to a conventional engine lathe comprising the bed 1 supported on suitable legs 2 and having a headstock 3 mounted on the bed, and a tool carriage 4 mounted for longitudinal movement on the ways 5 of the bed. The 40 lathe apron 6, for controlling the motion of the carriage 4 and cross slide 7, is mounted on the carriage 4 at the front of the lathe in the usual manner. The rapid traverse control box 8 for the apron mechanism is mounted on the left 45 hand end and on the front of the lathe bed 1.

Rapid traverse control box

Referring particularly to Figs. 3, 4, and 5, the 50 source of power for operating the apron mechanism to feed the carriage 4 and cross slide 7 is derived from the headstock transmission in the usual manner through the gears 9, 10, and 11 properly mounted on the left hand end of the lathe. The feeding power is delivered to the 55

apron mechanism from the rapid traverse control box 8 through the usual feed rod 12 which is coupled by suitable means 13 to the feed drive shaft 14 journaled in suitable bearings 15 and 16 in the rapid traverse control box 8, which shaft 14 has the gear 17 fixed thereto. This gear is driven by the gear 11 so as to transfer power from the headstock transmission to drive the feed rod 12 as will be readily understood.

In this novel arrangement the usual rack and pinion means for longitudinal feeding of the carriage has been dispensed with. In their stead a circular helical rack or rapid traverse screw 18 is provided, located longitudinally of the lathe bed 1, and adapted to be rotated in either direction at a relatively rapid rate for rapidly traversing the carriage in either direction. It is stopped during the normal feeding of the carriage 4. The left-hand end of the rapid traverse screw 18 is journalled in suitable bearings 19 and 20 mounted in the rapid traverse control box 8. A suitable anti-friction thrust bearing 21, mounted adjacent the bearing 19 and also a similar thrust bearing provided in the right hand end mounting (not shown) of the rapid traverse screw 18, may be employed to prevent axial movement of the screw during the feeding and rapid traverse motions of the carriage 4.

The means for driving the rapid traverse screw 18 in either direction comprises the clutch shaft 22 journaled in suitable bearings 23 and 24 mounted in the rapid traverse box 8 and having a suitable driving pulley 25 mounted thereon which is driven at all times during the operation of the lathe. Rotatably journaled on the bearing portions 26 and 27 of the clutch shaft 22 are the forward and reverse clutch members 28 and 29 which may be alternately connected in driving engagement with the shaft 22 by actuation of the conventional multiple-disc clutches 30 and 31 upon axial movement of the usual clutch actuator spool 32. Formed integral with the clutch members 28 and 29 are gears 33 and 34. The gear 34 is adapted to drive the gear 35 fixed on the rapid traverse screw 18, and the gear 33 is adapted to drive the idler gear 36 rotatably mounted on the stud 37 fixed in the rapid traverse box 8, which idler gear 36 in turn drives the gear 38 fixed on the rapid traverse screw 18 (see especially Fig. 3). It can therefore be seen that by rendering either one or the other of the multiple-disc clutches 30 and 31 operative, as described, the rapid traverse screw 18 may be caused to rotate in either direction. During normal operation of the lathe, when no rapid traversing is being performed, the spool 32 is in neutral position, rendering both multiple-disc clutches inoperative, so that the rapid traverse screw is normally not rotating while carriage feeding operations are taking place.

Apron transmission

Referring particularly to Figs. 6, 7, and 8, the feed rod 12 passes through the cone gear sleeve 39 which is journaled in the bearings 40 and 41 in the apron 6. A key 42, fixed in the sleeve 39 and slidably fitting in the keyway 43 in the feed rod 12, provides means whereby the sleeve 39 may be rotated by the feed rod 12 while at the same time permitting longitudinal movement of the apron 6 and carriage 4. Fixed to the sleeve 39 intermediate the bearings 40 and 41, and adjacent the latter, is a cone of gears 44.

Mounted parallel with the sleeve 39 is the dive-key shaft 45 rotatably journaled in the

bearings 46, 47, and 48 in the apron 6, the bearings 46 and 47 being adapted to prevent substantially all axial movement in the shaft 45. Rotatably journaled on the bearing portion 49 of the shaft 45 intermediate the bearings 46 and 47, and adjacent the latter, is a series of gears 50 adapted individually to engage the gears of the gear cone 44 in driving relationship so that they rotate at all times during the rotation of the cone of gears 44. Suitable spacing collars 51, 10 52, and 53 and the gear sleeve 54 fixed on the shaft 45, keep the gears 50 in proper axial alignment at all times with the cone of gears 44.

A dive-key 55, adapted to slide axially of the shaft 45 in a suitable keyway 56 and urged radially outward from the center of the shaft by a suitable spring 56a, provides means whereby any one of the gears 50 may be connected in driving relation to the shaft 45. This is of course accomplished when the nose 57 of the dive key 55 engages a slot 58 (Fig. 10) in one of the gears 50. A novel feature of this arrangement is that a plurality of slots 58 are provided in the gears 50 to permit more rapid engagement of the dive-key 55 with one of the gears 50 when the dive key 55 is shifted to a selected position. Another novel feature is that the driving faces 59 of the slots 58 in the gears 50 are not parallel but are arranged to diverge inwardly toward the center of the shaft 45, the nose 57 of the dive key 55 being made wedge-shaped so as to fit snugly between the faces 59 of the slots 58 when fully engaged therein. The purpose of this is to permit quick engagement and easy withdrawal of the dive key even while the lathe is taking heavy cuts, an advantage not possible in former constructions wherein the driving faces 59 were arranged parallel. The mechanism just described provides the speed changes for obtaining the fine range of feeds and threads. 40

In order to give the complete range of feeds and threads necessary to a lathe, mechanism providing a series of coarse feed and thread changes are utilized in addition to the fine changes above described. This mechanism comprises a shaft 60 journaled in suitable bearings 61 and 62 and confined thereby from substantially all axial movement, mounted in the apron 6 parallel to the shaft 45. Fixed to the shaft 60 are three different sized gears 63, 64, and 65, the largest gear 63 being constantly engaged with the gear 66 formed integral with the sleeve 54 so that rotation of the shaft 45 will cause rotation of all the gears 63, 64, and 65 and the shaft 60.

Located parallel with the shaft 60 is the bevel pinion shaft 66, journaled in the bearing 67 in the apron 6 and having a bevel pinion 68 fixed to the end opposite the bearing 67, which pinion 68 in turn is journaled in the bearing 69 in the apron 6. The bearings 67 and 69 are so arranged as to prevent substantially all axial movement in the shaft 66. The portion of the shaft 66 intermediate the bearings 67 and 69 is provided with splines 70 upon which is slidably mounted the multiple sliding gear 71, comprising the gears 72, 65 73, and 74 which gears are adapted respectively to engage the gears 63, 64, and 65 of the shaft 60 so that three major speed changes may be obtained between the shafts 60 and 66 when the proper axial position is selected for the multiple sliding gear 71.

The means for driving the leadscrew 75 for the thread chasing from the change speed mechanism described comprises a sleeve 76 rotatably journaled in suitable bearings 77 and 78 in the 75

apron 6 and a gear 79 fixed to the sleeve 76 which is driven by the gear 80 slidably mounted on the splines 70 of the shaft 66. The gears 79 and 80 may be disengaged or engaged at will by sliding the gear 80 axially on the splines 70. The leadscrew is slidably supported in the bore of the sleeve 76, a key 81 fixed in the sleeve 76 being adapted slidably to engage the keyway 82 of the leadscrew 75 so that the leadscrew 75 can be driven at any time during longitudinal movement of the apron 6. The means for engaging the half-nuts 83 on the leadscrew 75 comprises the usual scroll cam 84, cam shaft 85, and hand lever 86 as fully disclosed in Patent 980,971 issued Jan. 10, 1911.

The mechanism for alternately effecting longitudinal and cross feeding of the carriage and cross slide is substantially the arrangement set forth in Patents 1,218,784 issued Mar. 13, 1917 and 1,944,231 issued January 23, 1934. The bevel pinion 68 is arranged to drive the bevel gear 87 fixed on the shaft 88 suitably journaled in the front and rear walls of the apron 6. Fixed on the shaft 88 is the pinion gear 89 which drivingly engages the shiftable double clutch gear 90 fixed to the shifter shaft 91 by a suitable pin 92, the shifter shaft 91 being journaled for both rotary and axial movements in bearing bushings 93 and 94 mounted in the front and rear walls of the apron 6. Rotatably mounted on a projecting bearing portion 95 of the bushing 93 is the cross feed clutch gear 96 which engages the pinion gear 97 on the cross feed screw 98. Rotatably mounted on the shifter shaft 91 adjacent the bushing 94 is the longitudinal feed clutch gear 99 having the pinion gear 100 formed integral therewith. This is adapted to drive the gear 101 fixed to worm shaft 102 journaled in suitable bearings 103 and 104 in the front and rear walls 40 of the apron. The worm 105 fixed to the shaft 102 adjacent the bearing 104 engages the rapid traverse screw 18 as a pinion engages a rack so that the apron 6 and carriage 4 are moved longitudinally upon rotation of the shaft 102. Pins 106 loosely carried in holes 107 in the double clutch gear 90 are used to keep the clutch gears 96 and 99 in proper axial position relative to the double clutch gear 90. It can thus be seen that when the double clutch gear 90 is moved axially 50 to engage the clutch gear 96 the cross slide will be actuated and when the double clutch gear 90 is moved axially to engage the clutch gear 99 the apron and carriage will be actuated for longitudinal feeding.

55 *Apron control mechanism*

A new and simplified control handle 108, for shifting the double clutch gear 90, has a hub portion 109 which is journaled in the bore 110 in the bushing 93 and has a bore through which the reduced end 111 of the shifter shaft passes. A suitable lock nut 112 threaded to the end of the shaft 91 serves to position the handle 108 axially on the shaft 91 by confining the hub portion 109 between the lock nut 112 and the shoulder 113 of the shaft 91, while at the same time permitting rotation of the reduced portion 111 of the shaft in the hub portion 109. On the periphery of the hub portion 109 is provided a cam slot 114 which is engaged by a pin 115 threaded in the apron 6 and passing through the bushing 93. The cam slot 114 is so arranged that as the hub portion 109 is rotated by means of the handle 108, the hub portion 109 and the shifter shaft 91 connected thereto will be shifted axially.

The arrangement is such that both the longitudinal and cross feed is disengaged when the handle 108 is in the down position as shown particularly in Figs. 1, 2, 7, and 8. When it is desired to engage the longitudinal feed, the handle 5 108 is moved upward to the right and when it is desired to engage the cross feed the handle 108 is moved upward to the left. A conventional spring-backed ball detent 116 is provided to coact with appropriate notches 117 in the hub portion 109 properly to retain the handle 108 in the longitudinal feed, cross feed, and neutral positions.

A simplified interference device, Fig. 8, is provided between the half-nuts 83 and shifter shaft 15 91 comprising a rod 118 slidably fitting in suitable bores 119 and 120 in the apron 6. An annular slot formed on the shifter shaft 91 permits the rod 118 to move radially toward the axis of the shaft 91 only when the shifter shaft 91 and 20 the double clutch gear 90 are in neutral position, under which condition the other end of the rod 118 is withdrawn from the notch 122, allowing manipulation of the half-nuts 83 for engagement with or disengagement from the leadscrew 25 75. When the half-nuts 83 are engaged, the slot 122 does not line up with the rod 118 so that the rod 118 cannot be moved out of the slot 121 thus preventing the shaft 91 from being moved axially 30 so as to engage the feed. With the half-nuts 83 35 withdrawn, the rod 118 can enter the slot 122 of the half-nuts 83 and will be held in the slot 122 whenever the shifter shaft 91 is moved to either feed engagement position, which precludes any possible engagement of the half-nuts 83 when 40 any feed position is selected.

The apron 6 has the usual hand wheel 123 for manual longitudinal movement of the apron 6 and carriage 4. This is mounted on the hand wheel shaft 124 journaled in suitable bearings 40 125 and 126 in the apron 6. The shaft 124 is connected at all times to the longitudinal feeding transmission through the gear 127 fixed on the hand wheel shaft 124, and the idler gear 128 journaled on a suitable bearing 129 on the shaft 45 130 fixed in the apron 6. The idler gear 128 in turn is in driving engagement with the longitudinal feed clutch gear 99. Thus, through the mechanism described, the apron 6 and carriage 4 may be manipulated longitudinally at all times 50 by manual rotation of the hand wheel 123.

Referring particularly to Figs. 1, 2, 6, 7, and 11, the means for selecting the fine speed changes in the apron transmission for the various threads and feeds desired comprises the control lever 131 55 mounted on the rock shaft 132 on the front of the apron 6. On the inner end of the rock shaft 132 is fixed the gear 133 which engages the circular rack 134 of the dive key shifter sleeve 135 which sleeve 135 is slidably mounted on the dive-key shaft 45 and is caused to rotate therewith by means of the key 136 fixed in the shaft 45 and slidably engaging in the keyway 137 of the sleeve 135. The sleeve 135 is connected to the dive key 55 by means of the screw 138 threaded 60 in the sleeve 135 and projecting inwardly to engage the notch 139 provided in the outer end of the dive key. It can thus be seen that by swinging the handle 131 the gear 133 will be rotated. This in turn will cause axial movement in the 65 sleeve 135 and the dive key 55 connected thereto, whereby to engage the various gears 50 in driving relation on the shaft 45 as already described. Suitable retaining means for holding the lever 131 in selected position comprise the usual spring- 70 75

seated plunger handle 140 having the plunger 141 adapted to engage the locating holes 142 corresponding to the various gears 50.

The means for selecting the coarse changes of speed in the apron transmission for the various threads and feeds desired is clearly shown in Figs. 1, 2, 6, and 9 and comprises the control lever 143 which is mounted in the rock shaft 144 on the front of the apron 6. On the inner end of the rock shaft 144 is fixed a lever arm 145 having pivotally mounted at its outer end a shifter yoke 146 which engages the side faces of the gear 74 of the sliding gear 71 so that movement of the lever 143 will cause sliding of the gear 71 selectively to engage the various combinations of gears 63—72, 64—73, and 65—74 as already described. The usual spring-seated plunger handle 147 is provided for the lever 143 having the plunger 148 adapted to engage the locating holes 149 corresponding to the gear combinations indicated above. It is to be noted that the index plate 150 for selecting the positions of the levers 131 and 143 for the desired feeds and threads is conveniently located for the operator on the front of the lathe apron.

This feed mechanism for a lathe is unique in that the leadscrew 75 for thread chasing is driven from the apron transmission rather than from transmission mechanism fixed to the bed 1 of the lathe. In the apron is provided means whereby the leadscrew 75 may be alternately connected or disconnected from the apron transmission mechanism. Referring particularly to Figs. 1, 2, 6, and 10, a lever 151 is mounted on the rock shaft 152 on the front of the apron 6. On the inner end of the rock shaft 152 is fixed a lever arm 153 which has a shifter yoke 154 pivotally mounted on its outer end which in turn engages the side faces of the gear 80 so that movement of the lever 151 will cause the gear 80 to be moved axially on the splines 70 of shaft 66 to engage or disengage the gear 80 from the gear 79.

As described above, the longitudinal feeding of the apron 6 is accomplished by slowly rotating the shaft 102 and the worm 105 fixed thereon by means of the power feed mechanism or the hand-wheel 123, the worm 105 rolling axially along the rapid traverse screw 18 in the manner of a rack and pinion. When it is desired longitudinally to rapid traverse the apron 6 and carriage 4 in either direction the rapid traverse screw 18 is rotated in either direction at a relatively rapid rate while the shaft 102 and the worm 105 are held from rotating. In this case the worm 105 functions as a nut which is caused to travel axially along the rapid traverse screw 18 so as to move the apron 6 and carriage 4 longitudinally in rapid traverse motion.

The control mechanism for actuating the driving means for rotating the rapid traverse screw 18 in either direction comprises the rapid traverse control lever 155 which is pivotally mounted on a suitable stud 156 for up and down motion on the left hand end of the apron 6, Figs. 1, 2, 4, and 13. The control handle 155 is connected by means of the rod 157 to the lever arm 158 pivotally mounted in the depending boss 159 of the apron 6. The lever arm 158 is secured from axial motion in the boss 159 by suitable retaining means 160 and has a bore 161 in which is fixed the key 162 which arrangement slidably receives the periphery and keyway of the rapid traverse control rod 163, with the result that the rod 163 may be rocked in either direction by manipulat-

ing the lever 155 irrespective of whether the apron 6 is stationary or moving longitudinally.

The left hand end of the rapid traverse control rod 163 is journaled in the depending boss 164 of the control box 8. On the end of the control rod 163 adjacent the boss 164 is fixed the lever arm 165 which is connected by the rod 166 to a bell-crank lever comprising the arms 167 and 168 pivotally mounted on the shaft 169 in the control box 8. Suitable means 170 is provided on the end of lever arm 168 to engage in the annular slot 171 for axial movement of the sleeve 32 to engage the clutches 30 and 31. It can thus be seen that by moving the lever 155 up or down one or the other of the clutches 30 and 31 is rendered effective to cause rotation of the rapid traverse screw 18.

It is to be noted that longitudinal rapid traverse will only be imparted to apron 6 (when the rapid traverse screw 18 is rotating) providing the worm 105 on the shaft 102 is held against rotation. Means is provided for automatically preventing rotation of the worm 105 when the apron is being rapidly traversed in either direction. Referring particularly to Figs. 2, 4, 8, 9, and 13, a brake shoe 172 having a hub portion 173 pivotally mounted on a shaft 174 fixed in the apron 6 is adapted to contact the periphery of the gear 127. Slidably mounted in suitable bores 175 and 176 in the apron 6 and passing through a clearance hole 177 in the depending actuating lever 178 formed on the hub 173, is the brake actuating plunger 179. A spring 180 surrounding the plunger 179 between the bore 175 and the depending lever 178 provides a yielding means to hold the brake shoe 172 normally from contact with the periphery of the gear 127. Another spring 181 is also provided around the plunger 179 between the depending lever 178 and the collar 182 fixed to the shaft 179, the purpose of which is to provide resilient means for holding the brake shoe 172 on the periphery of the gear when the plunger is moved axially to the right, Fig. 8. The plunger 179 projects outwardly from the bore 176 in the apron 6, and has a pointed end 183 which is engaged by the V-notch 184 formed on the lug 185 depending from the rapid traverse lever 155. When the traverse lever 155 is in neutral position the pointed end 183 of the plunger 179 is fully entered into the V-notch 184 so that the plunger is fully extended to the left, disengaging the brake 172 from the gear 127. When the traverse lever 155 is moved either up or down to cause traversing of the apron, the pointed end 183 will be caused to ride up the tapered sides of the V-notch 184 so that the plunger 179 will be moved to the right engaging the brake shoe 172 on the gear 127. This, through the gears 127, 128, 99, 100, and 101, automatically prevents rotation of the worm 105 when the traverse mechanism is actuated. The tension of the spring 181 is such as to apply pressure of the brake shoe 172 on the gear 127 of just sufficient amount to hold the worm 105 from rotation through the gears noted above during normal traversing operations. Should the apron 6 and carriage 4 be traversed into an obstruction, such as the headstock 3, the shoe would slip on the gear 127, the gears above then being rotated by the rapid traverse screw 18 driving the worm wheel 105, thus preventing damage to the lathe mechanism.

It is to be further noted that rapid traversing of the apron 6 and carriage 4 can be accomplished without the use of the automatically operated 75

braking device just described merely by manually holding the handwheel 123 from rotation. The effort required upon the part of the operator to hold the hand wheel 123 during traversing operations is negligible because of the large reduction gearing existing between the worm 105 and traverse screw 18, the gears 101 and 100; and the gears 99 and 127.

It is also noted that the longitudinal and cross feeding mechanism may be engaged at any time, the engagement of the longitudinal feeding motion by engagement of clutch gear 90 with clutch gear 99 serving as a means to prevent substantially all rotation of the worm 105 as necessary 15 when traversing the apron 6. The relatively slow rotation of the worm 105 due to the feeding mechanism has substantially no effect upon the much more rapid motion produced in traversing. It can therefore be seen that the apron 6 and carriage 20 4 can be rapidly traversed at all times whether the feed mechanism be engaged or not without in any way damaging the mechanism of the lathe.

In the event the rapid traverse mechanism be engaged at the same time the half-nuts 33 are 25 engaged on the lead screw 15 no damage would result to the lathe mechanism as the gearing between the worm 105 and the shaft 126 will merely rotate at high speed, spinning the handwheel, the brake shoe 172 being insufficient to stop such 30 rotation of the gear 127. Thus the operator will have an indication that the lathe is not being operated properly.

Having described our invention what we claim as new and desire to secure by Letters Patent is:

1. In a lathe, a bed, a carriage movable thereon, an apron mounted on said carriage, a rotatable screw mounted on said bed against relative axial movement and parallel to the path of movement of said carriage, means for rapidly rotating said screw, a rotatable shaft mounted in the apron transversely of said screw, a worm gear fixed on said shaft and engaging said screw, means for manually rotating said shaft to effect a longitudinal movement of said carriage on the bed, and means for holding said shaft against rotation whereby to effect a rapid traverse of said carriage when said screw is rotating.

2. In a lathe, a bed, a carriage reciprocable thereon, an apron mounted on said carriage, a rotatable screw mounted on said bed against relative axial movement and parallel to the path of reciprocation of said carriage, means for rapidly rotating said screw selectively in both directions, a rotatable shaft mounted in the apron transversely of said screw, a worm gear fixed on said shaft and engaging said screw, means for manually rotating said shaft to effect a longitudinal movement of said carriage in either direction on the bed, and means for holding said shaft against rotation whereby to effect a rapid traverse of said carriage in either direction when said screw is rotated in one or the other directions, said means comprising a brake.

3. In a lathe, a bed, a carriage reciprocable thereon, an apron mounted on said carriage, a rotatable screw mounted on said bed against relative axial movement and parallel to the path of reciprocation of said carriage, means selectively to effect rapid rotation in either direction and non-rotation of said screw, a rotatable shaft mounted in the apron transversely of said screw, a worm gear fixed on said shaft and engaging said screw, means for rotating said shaft in either direction, and means for holding said

shaft against rotation, whereby said carriage may be actuated in rapid traverse when said screw is rotating and said shaft is held from rotating, and whereby said carriage may be actuated for feeding when said screw is non-rotating and said shaft is rotated.

4. A tool feed mechanism comprising a frame member, a tool support member reciprocable thereon, a rotatable screw mounted on one of said members against relative axial movement and parallel to the path of reciprocation of said tool carrier, means for rotating said screw, a rotatable shaft mounted on the other of said members transversely of said screw, a worm fixed on said shaft and engaging said screw, and means for rotating said shaft, whereby said support member may be actuated in rapid traverse when said screw is rotated and said shaft is non-rotating, and whereby said support member may be actuated for feeding when said screw is non-rotating and said shaft is rotated.

5. A tool feed mechanism as set forth in claim 4 in which the tool support member is actuated in rapid traverse when said screw and said shaft are simultaneously rotated.

6. A tool feed mechanism comprising a frame member, a tool support member reciprocable thereon, a rotatable screw mounted on one of said members against relative axial movement and parallel to the path of reciprocation of said tool carrier, means for rotating said screw, control means for rendering said means for rotating said screw effective, a rotatable shaft mounted on the other of said members transversely of said screw, a worm fixed on said shaft and engaging said screw, means for rotating said shaft, and means actuated by said control means for holding said shaft against rotation when said screw is rotating.

7. In a lathe, a bed, a carriage movable thereon, an apron mounted on said carriage, a rotatable screw mounted on said bed against relative axial movement and parallel to the path of movement of said carriage, means on said bed for rotating said screw, a rotatable shaft mounted in the apron transversely of said screw, a worm fixed on said shaft and engaging said screw, manual and power means for rotating said shaft, means for alternately engaging or disengaging said power means, and means for arresting rotation of said shaft when said power means is disconnected.

8. In a lathe, a bed, a carriage movable thereon, an apron mounted on said carriage, a rotatable screw mounted on said bed against relative axial movement and parallel to the path of movement of said carriage, means mounted on said bed for rotating said screw, a rotatable shaft mounted in the apron transversely of said screw, a worm gear fixed on said shaft and engaging said screw, means for rotating said shaft, control means mounted on said apron for rendering said rotating means for said screw effective, a friction brake for holding said shaft against rotation, and means cooperating with said control means for rendering said rotating means and said friction brake simultaneously effective or ineffective.

9. In a lathe, a bed, a carriage movable thereon, an apron mounted on said carriage, a rotatable screw mounted on said bed against relative axial movement and parallel to the path of movement of said carriage, means for rotating said screw, a rotatable shaft mounted in the apron transversely of said screw, means for rotating said shaft, a worm gear fixed on said shaft and en-

gaging said screw, means for rotating said shaft, and means for holding said shaft against rotation when said screw is rotating whereby to effect a rapid traverse of said carriage, said holding means being ineffective to hold said shaft against rotation during rotation of said screw when said carriage is obstructed from free rapid traverse motion.

10. In a lathe, a bed, a carriage mounted thereon, an apron mounted on said carriage, a feed rod rotatably mounted longitudinally of said bed, means for rotating said feed rod, change speed gearing in said apron comprising a cone of gears driven by said feed rod, a shaft, a plurality of 15 gears journaled on said shaft and arranged to be driven by said cone of gears, dive-key mechanism adapted selectively to connect each of said plurality of gears in driving relation to said shaft, a second shaft rotatably mounted parallel with 20 said first mentioned shaft, a multiple-gear mounted on said second shaft and adapted to be driven by said first mentioned shaft, a third shaft rotatably mounted parallel with said aforementioned shafts, a second multiple-gear 25 mounted in driving relation on said third shaft adapted selectively to engage said first mentioned multiple-gear to effect a change speed drive between said second and third shafts, and means driven by said third shaft to effect feeding motion in 30 said carriage.

11. In a lathe, a bed, a carriage mounted thereon, an apron mounted on said carriage, a feed rod rotatably mounted longitudinally of said bed, means for rotating said feed rod, a 35 leadscrew rotatably mounted longitudinally of said bed, change speed gearing in said apron comprising a cone of gears driven by said feed rod, a shaft, a plurality of gears journaled on said shaft arranged to be driven by said cone 40 of gears, dive-key mechanism adapted selectively to connect each of said plurality of gears in driving relation to said shaft, a second shaft rotatably mounted parallel with said first mentioned shaft, a multiple-gear mounted on said 45 second shaft and adapted to be driven by said first mentioned shaft, a third shaft rotatably mounted parallel with said aforementioned shafts, a second multiple-gear 50 slidably mounted in driving relation on said third shaft adapted to selectively engage said first mentioned multiple-gear to effect a change speed drive between said second and third shafts, means driven by said third shaft to effect feeding motion in said carriage, and means for rotating said leadscrew 55 from said third shaft.

12. In a lathe as set forth in claim 10, control means mounted on the front of the lathe apron

to actuate said dive-key mechanism at all times during the operation of the lathe.

13. In a lathe as set forth in claim 11, a control means mounted on the apron for actuating said dive-key mechanism, a control means mounted on the apron for shifting said second multiple-gear, and control means for rendering said means for rotating said leadscrew effective or ineffective.

14. In a lathe comprising a carriage, a leadscrew, an element shiftable on the carriage to connect or disconnect the leadscrew and carriage, feed-rod-connecting, carriage-feeding and cross-feeding mechanisms on said carriage, three members coaxially and severally rotatable on 15 said carriage with clutching means on their adjacent sides, the middle member being connected to the feed-rod-connecting mechanism and the other two members being connected, respectively, to the other two mechanisms and being 20 held in axially spaced relation as a unit distinct from the middle member as a second unit, and one of said units being axially shiftable selectively to clutch together either outer member and the middle member, and means shifted by 25 said shiftable unit to connect and disconnect the leadscrew and carriage and comprising a bar axially slidable in said carriage and adapted alternately to engage appropriate slots in said shiftable unit and shiftable element so as to 30 prevent shifting of said element except when said shiftable unit is in its mid-position, and preventing shifting of said shiftable unit from said mid-position when said element is in lead- 35 screw-connecting position.

15. In a lathe apron, a support and three mechanisms on the support, three members severally and coaxially rotatable on the support and connected, respectively, to said three mechanisms, the two outer members being held in 40 axially spaced relation as a unit distinct from the middle member as a second unit, the three members having positively engaging clutching means on their adjacent sides, one unit being shiftable axially to three different positions 45 selectively to clutch the middle member and either outer member together, a lever movable in a plane perpendicular to the axis of said shiftable member and axially confined on said shiftable member, cam means associated with said support and said lever adapted to cause said lever to be moved axially when moved in said perpendicular plane whereby to shift said axially shiftable unit to said different positions, and 50 detent means also associated with said support and said lever to hold said unit in each position.
